UNITED STATES PATENT OFFICE.

SAMUEL A. NEIDICH, OF PHILADELPHIA, PENNSYLVANIA.

INK-RIBBON MECHANISM.

SPECIFICATION forming part of Letters Patent No. 655,985, dated August 14, 1900.

Application filed September 11, 1899. Serial No. 730,083. (No model.)

To all whom it may concern:

Be it known that I, SAMUEL A. NEIDICH, of Philadelphia, in the State of Pennsylvania, have invented certain new and useful 5 Improvements in Ink-Ribbon Mechanism, whereof the following is a specification, reference being had to the accompanying drawings.

My invention relates to mechanism whereby an ink-ribbon may be detachably secured and automatically shifted in co-operative relation with a printing-press of ordinary construction.

My invention comprises simple and efficient ribbon-shifting mechanism and means whereby a signal may be automatically given by said mechanism when it becomes necessary to reverse the direction of traverse of the ribbon.

My invention also comprehends certain adjunctive devices arranged to facilitate the insertion and removal of the ink-ribbon with respect to said shifting mechanism, as hereinafter described.

In the accompanying drawings, Figure 1 is a sectional view of a printing-press, showing a convenient embodiment of my invention applied thereto. Fig. 2 is an enlarged sectional view of certain parts shown in Fig. 1. Fig. 3 is a longitudinal sectional view of one of the feed-rollers, showing an automatic signaling device in connection therewith. Figs. 4 and 5 show details of construction of the feed-rollers, &c. Fig. 6 is a fragmentary 35 sectional view showing the arrangement of the parts for manual operation of the ink-ribbon rollers. Fig. 7 is a view of the socket end of the roller shown in Fig. 6. Fig. 8 is a sectional elevation of the auxiliary ribbon 40 roller or spindle.

Referring to Fig. 1, A is the main frame of an ordinary printing-press, in which is mounted the driving-shaft B, provided with the band-wheel b and pinion b', the latter 45 gearing with the cam-wheel C and serving to rotate it. The eccentric stud c upon said wheel C is operatively connected by the link C' with the stud e upon the bed E to rock said bed upon e' in the frame A. The chase E', 50 containing the form of type E², is secured upon the bed E, and the platen D is given the proper movement by the rock-arm D',

whose roller d' is engaged in the cam-groove c' of said wheel C.

The to-and-fro motion of the bed E, imparted to it by the link C', &c., is transformed into oscillatory motion of the roller-frame F, concentric with said stud e, said frame F being pivotally connected at f with the roller-arm G, whose opposite extremity is pivoted at g upon the fixed frame A. The ordinary inking-disk H is mounted upon the bracket h, secured upon the bed E and intermittently rotated by the pawl-lever I, pivoted at h' on said bracket, said lever being rocked by the engagement of its roller i with the upper face of the frame F.

The above-described members of an ordinary printing-press form no part of but serve to actuate and co-operate with my improved mechanism, comprising the ribbon-feed rollers J and K, arranged upon the bed E, respectively above and below the chase E', to shift the ribbon L across the face of the type E², said rollers being respectively 75 rotated in alternation step by step by the pawl-levers j and k, which are respectively connected by the links J' K' with the ordinary disk-lever I, above described. It is to be understood, however, that my device may 80 be actuated by suitable connection with any other movable member of the press. The parts are so arranged that the desired oscillatory movement is imparted from said lever I to both of the pawl-levers j and k, so that 85 the ink-ribbon L may be wound upon either of said rollers, while the other rotates idly, the respective pawling devices being alternately engaged and disengaged, according to the desired direction of traverse of the ribbon L. I shall only describe in detail the 90 roller J and the parts connected therewith, it being understood, however, that the devices connected with the roller K are substantially counterpart thereto and correspondingly lettered on the drawings.

Referring to Figs. 3, 4, and 5, the ribbon-feed roller J is mounted in the brackets e² and e³ for rotation upon the fixed cone-bearings J² and J³. The pawl-lever j is fixed upon the pawl-disk j', which is loosely mounted upon the shank j³ of the bearing J³ and carries the pawl j², in position to engage the ratchet-wheel j⁴, which is also loosely mounted

upon said shank. The lug j^5 on the wheel J^4 is adapted for engagement in the slot j^6 of the bearing-plate j^7 on the roller J . The bearing-stud j^8 at the opposite extremity of said roller J is mounted to telescope therein, but is normally maintained in its extended position by means of the spring j^9 , being so arranged that the stud j^8 may be thrust inward to release the roller J from its bearings for removal. 5 As shown in Fig. 2, said rollers J and K are provided with hook-pins j^x k^x to positively engage the ends of the ink-ribbon L , which is extended from the roller J to the roller K over the face of the type E^2 in the chase E' 10 and depends over the guide-rod E^4 , upon which are secured adjustable spring-clips e^4 , which serve to guide and prevent its lateral displacement. 15

The arrangement of the parts above described is such that both of the pawl-levers j and k are operated by the lever I , &c., at each stroke of the bed E , and it being necessary to render one or the other of the pawls j^2 and k^2 inoperative in accordance with the direction of the traverse of the ribbon L , both of said pawls j^2 k^2 are arranged to be manually rotated upon their respective axes on the pawl-disks to the disengaged position indicated at j^2 in Fig. 2. In order that the operator may be warned when it is necessary to reverse the position of said pawls, I find it convenient to provide a signaling device, which is automatically operated, as follows: The roller J is conveniently made of wood or other non-conducting material, bored at J^4 to receive the wiring connections for the switch J^x . The bearing member j^8 being arranged to telescope within the metal sleeve j^{10} , enclosing the spring j^9 , said sleeve is electrically connected by the wire j^{11} with the spring j^{12} , which normally thrusts the non-conducting push-piece of the switch J^x into the position shown in Fig. 3. In said position the spring j^{12} makes electrical contact with the push-piece bushing j^{13} , which is electrically connected by the wire j^{14} with the bearing-plate j^7 at the opposite end of the roller J . Therefore whenever the push-piece is permitted to project, as shown in Figs. 2 and 3, 25 an electric circuit is established between the bearings J^2 and J^3 , and whenever the ribbon L is wound upon the roller the push-piece thrusts the spring j^{12} away from said bushing j^{13} and the circuit is broken. The brackets e^2 and e^3 being both secured upon the metallic bed E the bearing J^2 is insulated from its bracket e^2 , as indicated at j^{15} , in order to conveniently establish an exterior circuit from the bearing J^2 to the bearing J^3 . Said circuit comprises the wiring connections n n' , the bell or other signal M , the battery N , and the switch O . 50

Although I have diagrammatically shown the electric connections as applied only to the roller J , it is to be understood that both of the rollers J and K may be in electrical connection with the bell M , so that when the

ink-ribbon L has traversed the face of the type E^2 in either direction to the limit of its length the unwinding of said ribbon from one or the other of said rollers permits the respective switch J^x or K^x , to project, as indicated at J^x in Fig. 2, and thus the signal is operated automatically whenever it is necessary to reverse the pawls j^2 k^2 . 75

It is of course necessary to change the ribbon whenever a different color of ink is desired, and even if the press is operated continuously with a single color of ink it is necessary at intervals to renew the ribbon in connection with the rollers J and K , so that although said rollers are provided with means to permit of their removal from the press, as above described, I find it convenient to provide means to conveniently wind and unwind an ink-ribbon with respect to said rollers without removing them, as follows: As shown in Fig. 6, the bearing member j^8 of the roller J is adapted to be rotatively engaged by the crank-handle J^5 , the squared extremity of which is arranged to be entered in the similarly-shaped socket J^6 in said member j^8 through the bearing J^7 in the bracket e^2 . In this form of my invention said bracket may be conveniently insulated, as indicated at j^{16} . Said handle J^5 may be inserted and withdrawn at the will of the operator without disturbing the normal relation of the ribbon-feed rollers and the parts connected therewith. 95

As a temporary support for the roll of ribbon I provide an auxiliary roller or spindle P , which, as shown in Fig. 8, may be detachably mounted in the bearings p p' , secured upon the bracket h of the press. Said spindle P is provided with a crank-handle P' and is retained in proper position in the press by the engagement of its grooved collar p^2 with the bearing p' , the latter being open at the top to facilitate the insertion and removal of the spindle. The spring P^2 is fixed at its extremity p^3 in the recess p^4 in the spindle P intermediate of its length, and the free extremity p^5 of said spring is pointed for engagement with the ink-ribbon which is to be wound thereon. Although said spring P^2 suffices to prevent accidental displacement of the ink-ribbon, it is so proportioned as to permit of the removal of the roll of ribbon from said spindle in the direction of the arrow upon Fig. 8. 110

It being desired to remove or replace the ribbon with respect to the rollers J and K , an empty spindle P is inserted in the bearings p p' , and the ribbon L in the press having been wound upon one of said rollers J or K to the limit of its length its extremity is detached from the hook-pins j^x or k^x and engaged with the point p^5 of the spring P^2 of the spindle P and the latter rotated until said ribbon is wound upon said spindle P and unwound from the said feed-roller to the limit of its length, whereupon its extremity being detached from the hook-pins of the feed-roller and being completely wound upon said spin- 120 125 130

dle the latter is lifted from the bearing p' and withdrawn from the bearing p .

The ribbon which is to replace the ink-ribbon withdrawn as aforesaid being similarly mounted upon a spindle P , said spindle is inserted in the bearing p and its collar p^2 engaged with the bearing p' , and the free extremity of said ribbon being engaged with one of the feed-rollers the handle J^6 is inserted in the latter, as shown in Fig. 6 and above described, and said ribbon is wound upon said roller by manual rotation of said handle, while the spindle P idly rotates in the bearings p, p' . The inner extremity of the rolled ribbon thus unwound from the spindle P being extended over the type-form E^2 in the normal position shown in Fig. 2 and engaged upon the other of said feed-rollers, the automatic operation of the parts above described may be resumed.

It is to be understood that the mechanism hereinbefore described may be applied to any ordinary form of printing-press, and therefore I do not desire to limit myself to the precise construction and arrangement of the parts which I have illustrated, as it is obvious that various modifications may be made therein without departing from the spirit of my invention in accordance with the construction of the press in which said mechanism is to be embodied.

I claim—

1. The combination with an ink-ribbon feed-roller, of an ink-ribbon detachably secured thereon, means to unwind said ribbon from said roller, an electric switch connected with said roller, electric-circuit connections within said roller, and means to automatically operate said switch when said ribbon is unwound, substantially as set forth.

2. The combination with an ink-ribbon feed-roller, of an ink-ribbon detachably secured thereon, means to unwind said ribbon from said roller, an electric switch in said roller, electric-circuit connections within said roller, a signal connected with said switch, and means to automatically operate said switch and signal, when said ribbon is unwound, substantially as set forth.

3. The combination with an ink-ribbon feed-roller, of an ink-ribbon detachably secured thereon, means to unwind said ribbon from said roller, electric-circuit connections within said roller, an electric switch arranged to be depressed by the ribbon, when the latter is wound upon said roller, and means to automatically raise said switch when said ribbon is unwound, substantially as set forth.

4. The combination with two ink-ribbon feed-rollers, of means to alternately rotate said rollers, an ink-ribbon whose opposite extremities are respectively secured to said rollers, electric-circuit connections within said rollers, and electric switch mechanism in each of said rollers arranged to be alternately operated by the unwinding of the ribbon therefrom, substantially as set forth.

5. The combination with an ink-ribbon feed-roller, of respectively fixed and adjustable bearing members, carried by the opposite extremities of said roller, two bearings arranged for respective engagement with said fixed and adjustable members, mechanism to rotate said roller, and means to detachably connect said rotary mechanism with said roller, substantially as set forth.

6. The combination with an ink-ribbon feed-roller, of electric switch mechanism, mounted therein and arranged to be operated by an ink-ribbon wound thereon, and electric-circuit connections within said roller, substantially as set forth.

7. The combination with an ink-ribbon feed-roller, of bearings to detachably engage the respective ends thereof, one of said bearings being electrically connected with, and the other insulated from, its support, an electric circuit connecting said bearings with a source of electrical energy, and an electric signal, and electric switch mechanism, secured upon said roller and arranged to be operated by an ink-ribbon wound thereon, substantially as set forth.

8. The combination with an ink-ribbon feed-roller having bearing-sockets in its respective ends, of fixed cone-bearings arranged to support the respective ends of said roller, a pawl-disk, loosely mounted upon one of said fixed bearings, a pawl pivoted upon said disk, a ratchet-wheel loosely mounted upon said bearing, in operative relation with said pawl, means to detachably connect said ratchet-wheel with said roller in rotative engagement therewith, and means to intermittently actuate said pawl-disk, substantially as set forth.

9. The combination with an ink-ribbon spindle, having a recess in its periphery, of a spring-hook mounted in said recess, and arranged to normally project beyond the circumference of said spindle, and to be withdrawn within the circumference of said spindle to disengage the ribbon, substantially as set forth.

10. The combination with an ink-ribbon feed-roller, having a recess in its periphery, of means arranged in said recess to detachably engage a ribbon, a bearing member fixed at one end of said roller, a bearing member at the opposite end of said roller in telescopic relation therewith, a slot in one end of said roller, and roller-driving mechanism arranged for detachable engagement with said slot, substantially as set forth.

11. The combination with an ink-ribbon feed-roller, of means to detachably secure a ribbon thereon, bearings at the opposite ends of said roller, and a spring-pressed adjustable socket in one end of said roller arranged to rotatively engage an operating-handle, substantially as set forth.

12. The combination with an ink-ribbon feed-roller, of means to detachably secure a ribbon thereon, cone-bearings at the opposite ends of said roller, and a spring-pressed ad-

justable socket at one end of said roller, within said cone-bearing, arranged to rotatively engage an operating-handle, substantially as set forth.

5 13. In a printing-press, the combination with an ink-ribbon, of two feed-rollers to which said ribbon is normally secured at its opposite extremities, a ribbon-spindle auxiliary to said two feed-rollers, means to detachably secure said ribbon to said spindle, and means to rotate said rollers and spindle to transfer the ribbon from one to the other, substantially as set forth.

14. In a printing-press, the combination with an ink-ribbon, of two feed-rollers to which said ribbon is normally secured at its opposite extremities, a ribbon-spindle auxiliary to said two feed-rollers, means to detachably secure said ribbon to said spindle; bearings in said press to detachably secure said auxiliary spindle, and means to rotate said spindle in said bearing to transfer the ribbon to and from said spindle and rollers, substantially as set forth.

15 15. In a printing-press, the combination with an ink-ribbon spindle having a recess in

its periphery, of means secured in said recess to engage an ink-ribbon, a bearing-collar fixed at one extremity of said spindle, an operating-handle upon said spindle, and means to detachably secure said spindle in said press, substantially as set forth.

16. In a printing-press, the combination with an ink-ribbon, of two feed-rollers to which said ribbon is normally secured at its opposite extremities, an operating-handle arranged to be detachably engaged with said feed-rollers, a ribbon-spindle auxiliary to said two feed-rollers, means to detachably secure said ribbon to said spindle, an operating-handle upon said spindle, bearings for said roller and said spindle, arranged to permit of the rotary transfer of said ribbon to and from said spindle, and means to detachably secure said rollers and said spindle, in coöperative relation in said bearings, substantially as set forth.

SAMUEL A. NEIDICH.
